UNITED STATES PATENT OFFICE.

JAMES W. LAWLER AND ALBERT B. LAWLER, OF FREDERICKSVILLE, ILL.

DRAFT-EQUALIZER.

SPECIFICATION forming part of Letters Patent No. 268,912, dated December 12, 1882.

Application filed August 14, 1882. (No model.)

To all whom it may concern:

Be it known that we, JAMES W. LAWLER and ALBERT B. LAWLER, citizens of the United States, residing at Fredericksville, in the county of Schuyler and State of Illinois, have invented certain new and useful Improvements in Draft-Equalizers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has relation to improvements in draft-equalizers.

It consists in the combination and arrangement of the several parts, as will be hereinafter fully described, and specifically pointed out in the claim.

In the drawings, Figure 1 is a plan view, and Fig. 2 is a front edge view, of an equalizer constructed according to my invention.

Similar letters represent similar parts in both figures.

A represents the vehicle-pole. It may be connected to a wagon, car, harvesting-machine, or other vehicle, as is desired.

30 a a' represent two bars, having their inner endslapping each other, and pivoted on the bolt a², by which they are both secured to the pole or tongue A. These bars are extended on either side of the tongue A.

35 b b' are single-trees pivoted on the bars a a', near the outer ends of the latter, as shown. The bars a a' swing freely back and forth on their pivotal bolt a², as indicated in dotted lines.

40 c represents a lever-bar arranged some distance in rear of the pivotal bolt a², and pivoted on bolt c³ on the tongue, with one portion, c', about one-third its length, projected to the left, and the remaining portion or arm, c², about two-thirds its length, projected to the right, as shown.

d represents a pulley journaled in clip d', secured near the outer end of portion c' of bar c.

45 e represents a chain passed around pulley d, and having its ends made fast to bars a a' midway between the pivotal bolt a² and the point

where the single-trees are secured thereon, as shown.

f represents a bar arranged between the lever-bar c and the bars a a', and having one of its ends pivoted on bolt f' to the tongue A and its opposite end projected to the right beyond the end of the single-tree b on bar a, as shown.

f² represents a single-tree pivoted in clip f³, secured near the outer end of the bar f.

g represents a chain, having one of its ends made fast to the bar c, near the outer end of the latter, and its opposite end secured to the bar f about midway between the pivotal bolt f' and the clip f³.

i represents a bar or strap, having one end made fast to the tongue in front of the bars a a', and having its other end extended up above the bars a a', and provided with a bolt hole, 70 through which the bolt a² is passed, bracing the bolt a², as shown.

i' represents a flat bar or plate, having its rear end fixed on bolt f' and its forward end fixed on bolt a², and arranged between the bars a a', as shown in Fig. 2, whereby the bolts f' and a² are connected and braced and the friction of the bars a a' one against the other is prevented.

i² represents a brace plate or strap, having 80 one end secured to the tongue A in rear of the bar c and its other end carried up over the bar c, and provided with a bolt-hole, through which the bolt c³ is passed.

In the operation of our invention one horse 85 is connected to each of the single-trees b, b', and f². The bars a a', to which the single-trees b b' are secured, are preferably secured and turn on the same bolt. It will be understood, however, these bars may be pivoted on 90 separate bolts, and the result obtained may be equally as good. The horses attached to the single-trees b and b' are arranged next and on opposite sides of the pole, and by reason of the chain e being passed around pulley d they 95 work in opposition to each other. It will also be seen the pull of the two horses hitched to trees b and b' is exerted on the short arm c' of bar c, and the bar c, by its long arm c², being the point of application of the draft of 100 horse attached to bar f, the draft of the three horses is equalized, and when they are pulling

with equal force the bars a , a' , c , and f will stand in the position shown in full lines, Fig. 1, at right angles to the pole A. It will be seen that by removing the bars c and f and placing the pulley d , carrying the chain e , on the bolt c^3 , the equalizer is readily changed from a three to a two horse equalizer. By arranging the two horses next the pole to pull directly against each other better results are obtained, especially in turning corners, and by the arrangement described, whereby the two horses next the pole are balanced with the third horse, the difficulty of side draft is overcome, making the device especially useful on self-binding harvesters in which one horse moves close to the grain-row, and it is of great importance to have a direct forward movement of the machine.

It will be understood that instead of connecting the single-trees to the bars a a' , as described, the said bars may be provided with hooks or other means whereby the horses may be attached.

Having thus described our invention, what we claim, and desire to secure by Letters Patent, is—

The combination, with the double-tree and the lever f , of the double lever c , having its longer arm, c^2 , arranged in rear of the lever f , the anti-friction roller d , journaled on the end of the shorter arm of the lever c , the chain g , coupled to the longer arm of lever c and to the lever f , and the equalizing-chain e , having one of its ends made fast to one end of the double-tree and its other end carried around the anti-friction roller d and made fast to the opposite end of said double-tree, substantially as set forth.

In testimony whereof we affix our signatures in presence of two witnesses.

JAMES W. LAWLER.
ALBERT B. LAWLER.
